MARINE CATHODE

August P. Colaiaco and Spencer M. Cork, Pittsburgh, Pa., assignors to Westinghouse Electric Corporation, East Pittsburgh, Pa., a corporation of Pennsylvania

Application March 20, 1947, Serial No. 736,040

2 Claims. (Cl. 250—27.5)

1

Our invention relates to a vapor-electric device and particularly to means for substantially maintaining the cathode level in a vapor-electric device.

In the operation of vapor-electric devices, such as mercury-arc rectifiers, on movable platforms, such as on ocean-going vessels or on vehicles, considerable difficulty has been encountered because of the splashing about and the formation of waves on the cathode surfaces. Also because of the tilting of the containers because of the tilting of the platform on which they are mounted or because of sudden stopping or reversal of direction, it has been found desirable to provide such vapor-electric devices with so-called contoured cathode containers. These are cathode containers in which the upper surface of the cathode dish is contoured so that the liquid in the cathode dish will not spill over the lip at maximum inclination in the various directions, for instance, if the container is mounted on shipboard, the roll will be greatly in excess of the pitch of the vessel so that that portion of the lip which receives the roll will be materially higher than that portion of the lip which receives the pitch. It is thus possible to provide a cathode dish of restricted cross-sectional area and yet having a maximum arc-receiving opening so that the arc is substantially unrestricted in spite of the comparatively small cross-sectional area.

In these devices, it is also desirable to contour the bottom of the cathode dish so that at maximum inclination the bottom on the then upward side is just barely covered by cathode material. However, in the operation of vapor-electric devices, a certain quantity of material is required to maintain the operating condition. For example, a certain amount of the cathode material is within the arc space in the form of operating vapor and some of this vapor or rather the condensate thereof will be on the sides or condensing portions of the container and in the course of returning from the condensing surface to the cathode dish.

In normal operation, this quantity of displaced cathode material is substantially constant. However, when exciting devices, such as make-alive electrodes, are used, it is desirable to maintain the cathode surface substantially constant and when a relatively small cross-section of cathode dish is utilized, difficulty has been found because the quantities of cathode material necessary to maintain the operating characteristic of the device frequently produces an undesirable change in the cathode level. To eliminate this difficulty, we have provided this relatively small cathode

2

dish with a means for stabilizing the cathode level, preferably in the form of a reservoir, or a section of expanded cross-sectional area at the normal position of the cathode surface to provide a large quantity of cathode material at the surface level without greatly enhancing the total capacity of cathode material. This reservoir is preferably constructed by laterally expanding the cathode dish over a relatively short length at the point of normal cathode surface.

It is a further object of our invention to provide means for stabilizing the cathode surface in a vapor-electric device.

It is a further object of our invention to provide a cathode structure having an increased quantity of cathode material at the normal cathode surface.

Other objects and advantages of our invention will be apparent from the following detailed description taken in conjunction with the accompanying drawing, in which the figure is a fragmentary elevation partially in section of a vapor-electric device embodying our invention.

In the exemplary embodiment of our invention, 25 a vapor-electric device is provided having a substantially closed container 1 in the bottom 2 of which is secured a contoured cathode dish 3 of the type suitable for mounting on movable platforms and containing a liquid cathode 4 in the 30 form of a pool of cathode liquid, such as mercury. Cooperating with this cathode 4 is a suitable anode 5 supported in a known manner by an insulating device 6 attached to the top of the container 1. Suitable control or deionizing grids 7 35 may be placed between the anode 5 and cathode 4 and one or more control electrodes 8 for initiating the cathode spot may be inserted in contact with the cathode material and suitable keeping electrodes 9 may be utilized for maintaining 40 the cathode spot until the establishment of a main arc between the main anode 5 and the cathode 4. The cathode dish 3 is preferably of relatively small cross-sectional area and has the top 10 contoured to conform to maximum variation in the various directions. Also, the bottom 45 11 of the cathode dish 3 is also contoured to provide the minimum of cathode material. At the normal cathode level 12, a space 13 is provided for increasing the capacity of the cathode dish 50 per unit length thereof.

In the preferred embodiment, the cathode dish 3 has its diameter increased so that the surface area at the normal surface position 12 is increased to several times the normal cross-sectional area 55 of the cathode dish.

While we prefer to construct the cathode dish 3 with a unitary expanded portion 14, obviously other forms of reservoir at this particular location could be provided.

In the operation of the converter provided with our improved cathode dish, the evaporation of cathode material to provide the normal operating material for the converter will not materially reduce the cathode level as the extra cathode material at this point compensates for the transportation of cathode material. Consequently, the make-alive electrode 8 will be maintained in proper operating relation to the cathode surface for any normal operating condition.

While for purposes of illustration, we have shown and described a specific embodiment of our invention, it will be apparent that changes and modifications can be made therein without departing from the true spirit of our invention or the scope of the appended claims.

We claim as our invention:

1. In a vapor-electric device having a plurality of main electrodes at least one of which is a pool-type cathode, a make-alive electrode extending into contact with said cathode, a cathode dish of small liquid capacity for said cathode, said cathode dish being enlarged adjacent the normal position of the cathode surface.

2. An arc discharge device comprising a substantially evacuated container, a pair of cooperating main electrodes therein, one of said main electrodes being a pool-type electrode, a control electrode extending into contact with the cathode pool, a cathode dish containing the minimum volume of cathode material and means including an annular reservoir surrounding the cathode disk at the normal position of the cathode surface, said reservoir containing a quantity of cathode material there being openings for the passage of cathode material between the cathode disk and the reservoir to stabilize the level of the cathode material in the disk.
